UNITED STATES PATENT OFFICE.

WILLIAM JAMES ARMSTRONG, OF PATERSON, NEW JERSEY.

CHAIR WITH EXTENSIBLE FOOT-REST.

No. 868,633.

Specification of Letters Patent.

Patented Oct. 22, 1907.

Application filed September 15, 1906. Serial No. 334,719.

To all whom it may concern:

Be it known that I, WILLIAM JAMES ARMSTRONG, a subject of King Edward VII of Great Britain, residing at Paterson, in the county of Passaic and State of New Jersey, have invented certain new and useful Improvements in Chairs with Extensible Foot-Rests, of which the following is a specification, reference being had therein to the accompanying drawing.

The object of my invention is to produce a chair capable of adjustment so as to enable the occupant to enjoy the comfort derived from placing the body in a desired position that will stimulate a healthy circulation of the blood which is conducive to longevity.

The invention consists of an adjustable foot-rest capable of a horizontal as well as a vertical adjustment in relation to the seat of the chair to which it is attached.

The invention may be attached to a chair having either a movable back or seat and enables the occupant to support the limbs at the point and elevation desired to relieve fatigue and induce the rest and circulation required for the purpose.

In the accompanying drawings similar letters of reference indicate like parts.

Figure 1 is a section through the middle of a chair showing the improvement which is the subject of this invention. Fig. 2 is a view showing a section of the improved chair on the line A—A in Fig. 1, and Fig. 3 is an enlarged sectional view of the adjusting device.

In the drawings, 1 is the frame of the chair; 2, the legs; 3, the upholstering; and 4, the legs of the movable rest; 5 and 6 the upholstered portions of the foot rest.

The movable foot-rest is secured to the rod —7— which is slidably connected with the inner and outer sleeves —8— and —9— held by the support —10— pivotally secured to the frame of the chair and which is adjusted by the spring —11— and thumb-screw —12—.

The inner end of the outer sleeve 9 may be slightly raised or lowered owing to, and to compensate for, any unevenness of the floor and the spring 11 may be ad-

justed by a manipulation of the thumb-screw 12 so as to 40 form a cushion for the inner end of said sleeve. The spring therefore co-acting with the function of the hanging lever-support 10 form a compensating device that obviates the objectionable features resulting from a connection between the chair proper and the movable 45 foot-rest portion, were the sliding sleeve and rod and outer sleeve rigidly held in a horizontal plane.

The foot-rest is provided with a rack portion —13— which is engaged by the lever-pawl —14—, the end —15— being operated by hand or foot to release the 50 rack —13— when desired. Said lever-pawl is supported on the shaft —16— mounted in bearings —18—. The upper end of the pawl-lever is held in engagement with the rack-portion —13— by the spring —17—.

It is obvious that the legs may be held at the elevation desired which may vary according to conditions and circumstances.

My invention may be applied to a Morris or other chair.

With this description of my invention, what I claim 60 as new and desire to secure by Letters-Patent, is:—

In a chair having an extensible foot-rest, the combination with the frame having four fixed legs, of a pair of movable legs united so as to fit in between the front fixed legs when foot rest is not in use, racks which are vertically movable in said movable legs, a foot rest supported by said racks, pawl-levers secured to the movable legs and adapted to engage said racks to hold the foot rest at the elevation desired, a rod an inner and an outer sleeve forming a sliding connection between the chair proper and the movable foot-rest portion, a pivotal hanger supporting said rod and sleeves beneath the chair and a spring to adjust the plane in which the rod and sleeves lie, substantially as set forth.

In testimony whereof I affix my signature in presence 75 of two witnesses.

WILLIAM JAMES ARMSTRONG.
